[57] CLAIM

The ornamental design for table with removable container, as shown and described.

DESCRIPTION

FIG. 1 is a perspective view of a table with removable container, showing my new design, with the container removed for convenience of illustration; the sides not shown are identical to that shown.

FIG. 2 is a top plan view of the table without the container.

FIG. 3 is a bottom plan view of the table without the container.

FIG. 4 is an elevational view of the table which, in the form shown, has three substantially identical legs, a portion of the top removed and the container inserted.

FIG. 5 is a perspective view of the table with a portion of the top removed and the container inserted.

FIG. 6 is a top plan view of the table with a portion of the top removed and the container inserted.

FIG. 7 is an elevational view showing the table with the top in place and the container inserted; and,

FIG. 8 is a perspective view of the table with the container in place and the top in place.

A feature of the table is that it receives an upwardly open container which may serve as a planter for receiving real or artificial plants or flowers, or candles, or other decorative or functional items.
